UNITED STATES PATENT OFFICE.

CHARLES T. WITTSTEIN, OF CHICAGO, ILLINOIS.

DESIGN FOR A GEM-SETTING.

SPECIFICATION forming part of Design No. 36,622, dated November 17, 1903.

Application filed October 21, 1903. Serial No. 177,985. Term of patent 14 years.

To all whom it may concern:

Be it known that I, CHARLES T. WITTSTEIN, a citizen of the United States, residing at Chicago, in the county of Cook and State of Illinois, have invented a new and original ornamental Design for a Gem-Setting, which is fully shown by an enlarged perspective view in the accompanying drawing, forming a part hereof.

What I regard as new, and desire to secure by Letters Patent, is—

The herein-shown ornamental design for a gem-setting.

In testimony whereof I have signed my name to this specification in the presence of 15 two subscribing witnesses.

CHARLES T. WITTSTEIN.
